DESIGN FOR A HAT

Edward Wittcoff, University City, Mo.

Application March 9, 1938, Serial No. 75,702

Term of patent 7 years

To all whom it may concern:

Be it known that I, Edward Wittcoff, a citizen of the United States, residing at University City, county of St. Louis, State of Missouri, have invented a new, original, and ornamental Design for a Hat, of which the following is a specification, reference being made to the accompanying drawing, forming a part thereof, in which Figure 1 is a top plan view, Figure 2 is an edge elevational view, Figure 3 is an inverted plan view, and Figure 4 is a fragmentary sectional view taken approximately along the line 4—4, Figure 1, of a hat embodying my new design.

My design for a scalloped annular hat, fluted in radial swirls from the small ring in the center, is characterized by the fold at the crown-engaging portion, said fold extending upwardly and then arcuately outwardly and downwardly, as shown.

I claim:

The ornamental design for a hat, substantially as shown and described.

EDWARD WITTCOFF.
